HERBERT RÜHLEMANN, OF SOMMERDA, GERMANY, ASSIGNOR TO RHEINISCHE METALL-WAAREN-UND MASCHINENFABRIK, OF DUSSELDORF-DERENDOFF, GERMANY, A CORPORATION OF GERMANY

ELECTRIC IGNITER WITH CONDENSER AS STORING DEVICE FOR THE IGNITION CURRENT

Application filed October 10, 1931, Serial No. 568,175, and in Germany April 11, 1931.

The electric igniters or fuses, which in the form of percussion, time, or double igniters for projectiles, grenades, mines, or other bodies containing percussion charges, which carry the electrical energy necessary for igniting an igniting agent stored in condensers, contain two condensers connected in opposition to one another and with means for the mutual variation of the voltage of their stored energies, the difference of potential between which, which gradually increases to the magnitude required for the ignition voltage, is employed for igniting the igniting agent. For reasons of safety and in the case of time igniters also for the purpose of attaining a simple way of timing, the igniter is given the necessary electrical energy only shortly before use, from a source of voltage separate therefrom and only transiently connected thereto. In the case of igniters for projectiles this occurs at the instant of firing off the projectile, or during its passage through the bore of the gun, or only upon its leaving the mouth of the bore, in the case of grenades it occurs shortly after their release, during the falling out of the throwing device.

In the above noted well known igniters both igniting condensers must be charged and each of them requires for this purpose at least one special connecting contact element insulated with respect to the body of the igniter, both of which are to be placed into contact with the poles of a source of current. The possibility, however, exists that a defective making of the contact would allow only a single one of the igniting condensers to become charged and duds or pre-igniters will be the result. The same condition may also arise due to breaks in the charging circuits of the condensers during transportation, in the case of igniters which previously have left their points of manufacture in perfect condition. The known connections do not permit so shifting the electrical igniting means in the igniters that the leads thereto can be brought to the potential of the igniter body. Between the latter, thus also between the igniting means itself and the body of the igniter, a poten-

tial difference exists during at least the instant of charging, which, in the case of injuries to the leads, would lead to a pre-ignition during the charging. Percussion igniters with condenser devices of the above described type may furthermore give rise to duds, due to the fact that upon the entering of the igniter into a target the action of the material of the target upon the charging contact terminals produces a short-circuit between the two condensers, whereby the difference of potential thereof will become equalized before the percussion contact closure can produce the ignition.

The electrical igniter or fuse in accordance with the invention also contains a plurality of condensers used as storing means for the igniting current and has the advantageous properties of the above noted known igniters, such as simplicity, unlimited permanence in storage, safety in transportation and in shooting-off or throwing, the simplest possible timing means and extensive fields of usefulness. In the same, however, not the difference of potential formed between two condensers, but the voltage transmitted with delay to a single condenser, is used for igniting the igniting means. The new igniter has a condenser arrangement wherein a condenser which yields its energy as igniting current—hereinafter referred to as the "igniting condenser"—is connected to a second condenser which is chargeable by means of a source of current—known as the "storage condenser"—from which it receives its entire energy, or the partial energy still lacking for producing an ignition, by suitable means only after a certain delay after the completion of the charging of the storage condenser.

The source of current for providing the energy of the condensers may be arranged in the igniter itself and rigidly connected to the latter, preferably, however, separated in the above noted manner from the igniter, and only transiently connected thereto for delivering current thereto. Then the special advantage is obtained that only a single condenser of the igniter, namely the storage condenser, need be charged from the outside, which can be done in each individual case

with certainty. Due to this fact and due to the peculiar nature of the connections, the possibility of dangerous premature ignitions is absolutely excluded. The essential embodiments of the igniter for various types of ignition, and particularly advantageous details and possibilities of connection, which result in accordance with the general arrangement according to the invention, are 10 explained in greater detail in Figs. 1-13a of the drawings by the help of various exemplary embodiments and are discussed in detail hereinafter.

The figures show the diagrams of connections of projectile igniters and igniters for grenades in embodiments for percussion, time and double igniters of simple type, as well as such intended for special purposes. Similar elements of the various embodiments are 20 designated by similar reference characters.

The igniter in accordance with Fig. 1, for example a projectile percussion igniter, has two condensers *a* and *b* having the armatures *a*₁, *a*₂, *b*₁, *b*₂. *a* is the storage condenser, one 25 coating *a*₁ of which is connected with the body *c* of the igniter and whose second coating or armature *a*₂ is connected either directly or, for example, through a normally open inertia switch *d*₁, *d*₂, to a charging contact 30 element *e* insulated with respect to the body of the igniter. The second condenser *b*—the igniting condenser—is connected to the storage condenser *a* by a direct connection of its coating *b*₁ with *a*₁ and by connection of 35 its coating *b*₂ to *a*₂ through a high ohmic resistance *f*. An electric igniting agent *g* and a percussion closing contact *h* are connected in series across the igniting condenser *b*.

The electrical energy necessary for producing an ignition is obtained by the igniter after firing-off the projectile, upon leaving the mouth of the gun bore, from a stationary source of current, whose poles are connected, for example, to two contact springs *i*₁, *i*₂ projecting into the path of the projectile. During the acceleration of the projectile in the tube of the gun after the firing, the resiliently swingable contact element *d*₁ of the inertia switch *d*₁, *d*₂ is connected with its opposing 50 contact element *d*₂ (Fig. 1) and the outer charging contact *e* of the igniter is connected with the storage condenser *a*. Upon *e* brushing past the contact spring *i*₁ of the source of current and the simultaneous abutting of its second contact spring *i*₂ against the body of the igniter *c* the storage condenser *a* is charged to a definite voltage by the source of current. If the projectile has 55 left the mouth of the bore, the acceleration of the projectile ceases and the outer charging contact *e* of the igniter will be disconnected by the automatically opening inertia switch *d*₁, *d*₂ from the now charged storage condenser *a*. During the further flight of the 60 projectile the storage condenser *a* discharges 65

into the igniting condenser *b* through the resistance *f* and the latter gradually increases in voltage, while the storage condenser *a* loses the same. This procedure is illustrated in the voltage-time diagram of Fig. 1a. The storage condenser *a* hereby after its charging, at the time *t*=0 has an initial voltage *E*₁, which gradually decreases according to the logarithmic curve *S*_a as a result of the transfer of energy to the igniting condenser *b*. 75 The igniting condenser *b*, at the time *t*=0, thus directly after the charging of the igniter, has not yet any voltage, and such voltage grows therein only in accordance with the lines *S*_b and in accordance with the decrease 80 of energy of the storage condenser *a*. The voltage curves of the two condensers *a* and *b* asymptotically approach a mean end voltage *E*₂, the magnitude of which depends upon the ratio of the capacities of the two condensers *a* and *b* to one another. The larger 85 the capacity of the storage condenser *a* is chosen with respect to the capacity of the igniter condenser *b*, the higher will be the final voltage *E* as is shown by the dotted lines. 90

In order to ignite the igniting agent *g* (Fig. 1) a minimum voltage—the igniting voltage *E*_z (Fig. 1a)—is necessary in the igniter condenser *b*, which, measured from the instant of charging the igniter, is produced only after the lapse of a certain time *t*_z. Only after the lapse of this safety time period will the igniter have become capable of producing ignition. At that time it will already be at such a distance from the gun, 95 that an ignition produced by a premature closing of the percussion contact *h* will be free from danger for the gun and the gun crew.

As is clear from Fig. 1, one of the two lead wires leading to the igniting agent will be 10 at the potential of the body by the grounding to the body of the condenser armatures *b*₁, *a*₁. In case the other igniting agent wire should be injured and likewise have a ground, no danger of a premature ignition would exist 11 at the instant of charging the igniter. The igniting agent is then short-circuited and solely a dud is the result.

If, due to the striking of the igniter upon a target, an immediate short-circuit should 1 occur for any reason whatever in the charging circuit of the storage condenser *a*, then only the former will first discharge. A discharge of the igniting condenser *b* is so delayed and prolonged by the high resistance *f* that before a fall of voltage making ignition impossible can occur in the condenser *b*, even the most non-sensitive percussion switch, for example an inertia switch, will already have responded and brought about the ignition. 1

In the projectile percussion igniter in accordance with Fig. 2, which in general structure is similar to that of the one already described in accordance with Fig. 1, the percussion closing switch *h* is arranged between 1

the igniting agent *g* and the coating *b*₁ of the igniting condenser *b* which is connected to the body of the igniter *c*. Thereby a simple percussion closing switch is produced which, 5 for example, consists of a diaphragm switch in the point of the projectile, consisting of only a single metallic diaphragm *h*₁ arranged in the body of the projectile and an opposing contact element *h*₂ insulated with respect to 10 the body of the igniter.

The exemplary embodiments according to Figs. 3-5 relate to percussion igniters for hand grenades which, for example, at the instant of their release and falling-out of 15 the throwing device are provided with the necessary electrical energy by means of a charging plug connected to a source of current of suitable voltage. The general structure of the igniter corresponds to that of Fig. 1. The igniters furthermore, however, are provided also with a device which positively prevents the flowing of energy from the storage condenser *a* or from the source of current into the igniting condenser *b* during 20 the time the storage condenser is connected to a source of current.

For this purpose, in the igniter according to Fig. 3, a special switch is arranged in the circuit leading from the storage condenser *a* to the igniting condenser *b*. This consists of an intermediate contact member *k* which is shiftable by means of the charging plug *i*₁ from one connecting position, against spring pressure into a second position, and which 35 is insulated with respect to the body of the igniter *c*. In the normal position when the plug is not introduced into the igniter, the contact element *k* closes the circuit leading through the resistance *f* between the two condensers *a* and *b* by means of an end lug *k*₁ insulated with respect to its body, and is thereby itself out of contact with the supply leads to the storage condenser *a*. When the 40 charging plus *i*₁ is inserted, (Fig. 3) the contact member *k* is pushed inward to such extent that the connecting lead through the resistance *f* is interrupted between the two condensers *a* and *b*. Simultaneously the contact member *k* comes into contact with the 45 lead to the storage condenser *a*, provides a connection between the same and the "live" parts of the source of current, and the storage condenser *a* becomes charged. Only after the withdrawal of the charging plug *i*₁ and the disconnection of the live parts *k*-*i*₂ from the storage condenser *a*, will the connection 55 between *a* and *b* be again established automatically, and the igniter condenser *b* charged from the storage condenser *a*, to 60 make an ignition possible.

In the igniter, according to Fig. 4, the igniting condenser *b* is short-circuited during the charging of the storage condenser *a*, in order to prevent a current from flowing into 65 the igniter condenser, and thereby the ignit-

ing agent *g* is also short-circuited. This occurs by means of a pin *k*₁ secured to, but insulated from, the intermediate contact member *k*. After the insertion of the charging plug *i*₁ and the abutting of the now live intermediate contact member *k* produced thereby, 70 against one coating of the storage condenser *a*, the pin member *k*₁ short-circuits the igniting condenser *b* and the igniting agent *g* through the body *c* on the igniter, so that no 75 difference of potential capable of producing an ignition can occur between the two poles of the igniting agent. Upon withdrawing the plug *i*₁ after the completion of the charge of *a* the contact member *k* automatically is 80 brought out of contact with the conductor leading to the storage condenser *a* by means of the spring 15 acting thereon, the short-circuit of the igniter condenser *b* as well as of the igniting agent *g* is eliminated by the 85 sliding-off of the pin member *k*₁ from the short-circuit connection leading to *b* and the storage condenser *a* supplies energy to the igniting condenser *b*.

In Fig. 5 a percussion igniter is illustrated 90 wherein the two different devices for preventing a premature transfer of energy into the igniting condenser *b*, illustrated in Figs. 3 and 4, are combined into a single switch and produce the individual switching actions in 95 a definite order. An intermediate contact element *k* which is shiftable by the charging plug *i*₁ in opposition to a spring 15 from an outer connecting position into an inner one, has an extension comprising two metallic pin 100 members *k*₁ and *k*₂ insulated with respect to the same and with respect to one another. In the charging position of the intermediate contact member *k*, shown in Fig. 5, the forward pin portion *k*₂ of the latter short-circuits the 105 igniting condenser *b* and thereby the igniting agent *g*, through the body of the igniter, switches the igniting condenser *b* off by abutting of the insulating element 16 located between *k*₁ and *k* against the divided portion of the connection leading through the resistance *f*, from the storage condenser *a* and furthermore, by producing a contact between *k* and the lead passing through the storage condenser *a* connects the latter with the charging plug *i*₁ so that the storage condenser *a* 110 becomes charged. Upon passage of the contact element *k* into the second switch position, during the withdrawal of the charging plug *i*₁, first by the sliding-off of the still live contact element *k* from the lead to the storage condenser *a*, the latter is disconnected 115 from the charging plug *i*₁, and then by entry of the pin portion *k*₁ into the division point 120 of the lead passing from the storage condenser *a* through the resistance *f* to the igniting condenser *b*, the latter is connected to the storage condenser *a* to receive energy therefrom and finally the short-circuit of the ig- 125

niter condenser b , produced through the pin portion k_2 , is removed.

In the exemplary embodiment according to Fig. 6 all grounding to the body is avoided as well within the igniter as between the same and the charging plug. The igniter in this case for charging the storage condenser a has two charging contact elements k' and k'' insulated with respect to the body of the igniter.

In order to use the body of the igniter as a direct connection for the passage of current from the source lying outside of the igniter into the storage condenser and from the latter to the igniter condenser, or even only to bring the body of the igniter and one of the wires of the igniting agent to the same potential, the unipolar connection of the condensers with the body of the igniter may be produced also between the second coatings a_2 and b_2 , instead of to the two connected condenser coatings a_1 and b_1 , as shown, for example, in Fig. 7.

In Figs. 8 to 10 percussion igniters are illustrated which, for example in the form of igniters for hand grenades, have two complete condenser arrangements, each of which actuates a special igniting agency, in accordance with the invention.

The igniter, in accordance with Fig. 8, is capable of being set selectively to percussion ignition "with delay" or "without delay". For this purpose it is provided with two condenser arrangements A_m and A_o which are independent of one another, for example of the kind shown in Fig. 1, of which the arrangement A_o contains an igniting agent g_o , whose igniting beam upon closing the percussion switch h_o leads to immediate ignition of the explosive charge whereas in the second condenser arrangement, A_m , the igniting agent g_m first acts upon a delay device v . Each of the condenser arrangements has an insulated insertion socket with an intermediate contact element for introducing a charging plug i_1 ; the second pole i_2 of the source of current is connected to the body c of the igniter. The setting of the igniter to the desired type of ignition is accomplished by the particular nature of the charging. In order to provide a percussion ignition "with delay", for example by the sole insertion of a charging plug i_1 into the push socket of the condenser arrangement A_m , only the latter becomes charged, while the condenser arrangement A_o remains unconnected. For an ignition "without delay", on the other hand, both condenser arrangements A_o and A_m or only A_o are charged.

The percussion igniter in accordance with Fig. 9 has only a single push socket with an intermediate contact element, which upon the insertion of a charging plug i_1 thereinto, connects the storage condensers of both condenser arrangements A_o and A_m

to the source of current. Here also the setting of the device to the desired type of ignition is accomplished by charging either only the condenser arrangement A_m which operates "with delay" or both condenser arrangements A_o and A_m . This occurs automatically by the magnitude of the voltage fed to the igniter. In the lead to the storage condenser a of the condenser arrangement A_o for ignition "without delay" a discharge tube l_o is inserted, which permits a flow of current to the storage condenser from A_o and thereby the charging of the latter only when a charging voltage exceeding the break-down voltage of the tube l_o occurs. Then both condenser arrangements A_o and A_m become charged and the igniter gives instantaneous ignition upon impact. If the charging voltage is chosen smaller than the igniting voltage of the discharge tube l_o , then only the condenser arrangement A_m will receive current and ignition "with delay", is obtained. The discharge tube l_o instead of being arranged between the charging plug and the storage condenser a could also be connected at any of the points l_1, l_2, l_3 indicated in dotted lines or in the discharge circuit of the igniting condenser b of the condenser arrangement A_o .

The use of a plurality of condenser devices each instituting a special ignition effect may also be employed in order to make percussion igniters effective upon targets over water as well as targets located under water, without causing the igniter to produce an ignition upon striking the surface of the water. Such a throwable percussion igniter for action above and below water, shown, for example in Fig. 10, contains two condenser arrangements U and U_1 each provided with a storage condenser a and an ignition condenser b acting through a percussion closing switch h upon an igniting agent g , the storage condensers a of which are both charged when the device is thrown. The condenser arrangement U_1 acts in the case of targets above the water; after a short safety time interval its igniting condenser b has assumed the voltage necessary for producing an ignition upon striking a target above the water. If, however, the igniter lands in the water, then the igniting condenser b of U_1 is discharged by means of a water contact m which short-circuits the same, before the percussion closing switch h of U_1 , which operates somewhat more slowly, upon impact has also assumed the closed position necessary for ignition. The voltage still present in the storage condenser a of U_1 then likewise gradually becomes dissipated through the water contact m . The ignition condenser b of the condenser arrangement U for under-water action, on the other hand, becomes connected to its storage condenser a only upon the striking of the igniter upon water, by means of a water contact n , in order to pick up energy from

said condenser and only then, after a definite relatively short period of delay, will assume the voltage necessary for igniting the igniting agent g after a subsequent striking of the igniter upon an under-water target, through the resistance f , said period of delay being necessary for the settling to rest of the percussion closing switch h of U upon striking the water. A reverse discharge of the condensers a and b of the under-water igniting arrangement U is made entirely or partly impossible after the water short-circuiting between the discharged condenser arrangement U_1 for under water targets, by a discharge tube l or similarly acting means.

An igniter which is capable of being set for various types of ignition, for example the type shown in Figs. 8-10, may also, instead of being provided with a complete igniting arrangement for each type of ignition, have only two or more igniting condensers which deliver their energy in a definite manner as igniting current through electrical igniting agents, which are fed from a common storage condenser which can be charged from a source of current.

Fig. 11 shows such a throwing type igniter for operation "without delay" and "with delay", which uses in all, only three capacities. Therein an ignition condenser b_m dischargeable "with delay" through a percussion closing switch h_m and an igniting agent g_m , and furthermore a second igniting condenser b_o , likewise operating "without delay" through a percussion closing switch h_o and an igniting agent g_o , through a high ohmic resistance f_o and a discharge tube l_o connected in series therewith are connected to a common storage condenser a . At the instant of throwing of the igniter, only its storage condenser a is charged, namely with a small or large voltage in order to produce the desired type of ignition. With a small charging voltage not exceeding the break-down voltage of the discharge tube l_o , after the striking of the ignitor against a target an ignition "with delay" occurs because the storage condenser a has given off energy only to the igniting condenser b_m . The igniting condenser b_o has remained uncharged, because the discharge tube l_o has prevented a flow of current thereto through the resistance f_o . Only upon charging the storage condenser a to a voltage which exceeds the break-down voltage of the tube l_o will the igniting condenser b_o receive, after a definite safety time interval, a voltage sufficient for igniting the ignition agent g_o , so that upon impact upon a target an ignition "without delay" may occur.

The above noted connection with only one storage condenser is also advantageously usable for igniters for use above and below water as shown in Fig. 12. The igniter contains two ignition condensers b_e and b_u each operating through a percussion closing switch

h_e and h_u and an igniting agent g_e and g_u and capable of being supplied from a common storage condenser a through high ohmic resistances f_e and f_u . Only the storage condenser a is charged by means of a source of current, the former then during the flight of the projectile charging only the ignition condenser b_e through the resistance f_e . When the igniter strikes a target above the water accordingly the igniting agent g_e is ignited. Upon striking the water, on the other hand, the condenser b_e is discharged by means of a water contact o short-circuiting the igniting condenser b_e through the body c of the igniter before the condenser b_e produces an ignition through its percussion closing switch h_e . At the same time a second water contact p connects the second pole of the igniting condenser b_u to the storage condenser a . Through this connection namely a charging of the igniting condenser b_u occurs through the resistance f_u and upon the striking of the igniter upon an under-water target the igniting agent g_u is caused to ignite by closure of the switch h_u .

The igniter in accordance with Fig. 12 shows furthermore how, by the insertion of a percussion-closed switch and simultaneously a discharge tube into the discharge circuit of an ignition condenser, the energy thereof can be used for producing a percussion ignition as well as a time ignition. In parallel to the percussion-closed switch h_u and in series with the igniting agent g_u there is located in the discharge circuit of the condenser b_u a discharge tube l_u . If the igniter has struck neither an over-water target nor an under-water target, then the voltage which gradually increases continually in the igniting condenser b_u will eventually break down the discharge tube l_u as soon as it has reached the value of the break-down voltage thereof. Then a time ignition will occur automatically under water through the ignition agent g_u .

The voltage relationships within the condenser arrangement may be seen from the voltage-time diagram of Fig. 12a. The storage condenser a after its charging at the time $t=0$ has an initial voltage E_a , which decreases as a result of the transfer of energy into the igniting condenser b_e according to the curve S_e . The igniting condenser b_e at the time $t=0$ has as yet no voltage, and such voltage increases therein only in accordance with the line S_e . The ignition voltage E_e sufficient for igniting the igniting agent g_e has formed in the condenser b_e after the safety time interval t_e . From then on up to the striking of the igniter upon water at the time t_m , an operation of the igniter is possible upon striking targets above the water. Upon striking water the igniting condenser b_e loses its voltage very rapidly in accordance with the curve S_{ee} by short-circuiting through the water, whereas from this point on the second

igniting condenser b_u , heretofore remaining uncharged, becomes charged from the storage condenser a . The latter further loses voltage in accordance with the curve S_{aa} and in the ignition condenser b_u such voltage increases in accordance with the line S_u . After the safety time interval t_u , measured from the time of striking the water, this voltage has attained a magnitude sufficient for igniting the igniting agent g_u . Now ignition under water is possible, either upon striking a target, by closing the switch h_u , or upon failure to strike such target, an automatic time ignition would occur at the time t_2 after the voltage S_u in the condenser b_u has reached the break-down voltage E_1 of the break-down tube l_u and has broken down the said tube l_u .

In Fig. 13 the connection in accordance with the invention is shown applied to a pure time igniter, for example for projectiles. The structure of the igniter is similar essentially to that of the igniter according to Fig. 1. Only in place of the percussion closing switch of the latter it has a discharge tube l in the discharge circuit of the igniting condenser b . Furthermore the inertia switch d_1, d_2 is arranged between the storage condenser a and the outer charging contact e , for example as a two-way switch, in such way that it normally disconnects the contact e from the condenser a , thus providing the connection between the condenser a and the igniting condenser b through the resistance f , whereas only during the period of acceleration of the projectile, that is, at the instant of charging the igniter, does it interrupt the connection between a and b and connect the charging contact e to the condenser a . In the igniter likewise only the storage condenser a becomes charged, which then provides the igniting condenser b with energy through the resistance f . If the voltage in the same has grown to the magnitude of the break-down potential of the tube l , then a disruptive discharge of voltage occurs automatically through l , whereby the igniting agent g is ignited.

The setting of the igniter to a definite time of ignition takes place directly upon charging, by the nature of the current supply, namely by suitable determination of the charging voltage. For a short "time of travel" of the igniter a relatively high charging voltage is applied to its storage condenser a . Then a strong flow of current takes place toward the igniting condenser b and b will assume a voltage sufficient for breaking down the tube l after only a short time. Lower charging voltages will cause the flow of current from a to b through the resistance f to take place more slowly and thus longer "times of travel" of the igniter may be attained.

These relations are shown in the voltage-time diagram of Fig. 13a. An initial volt-

age E_a of the storage condenser a , upon gradual decrease according to the curve S_a and simultaneous increase of a voltage in the igniting condenser b , in accordance with the curve S_b , allows the igniting voltage E_2 necessary for breaking down the tube l to be built up after the time interval t_1 . A higher initial voltage E_{a1} in the condenser a provides, through its drop in voltage according to S_{a1} and through the increase in voltage S_{b1} in the condenser b , an earlier time of ignition at the time t_2 .

The timing of the igniter aside from varying the charging voltage or in addition to varying the charging voltage could also be accomplished by regulating the magnitude of the resistance of f , for which purpose f is constructed as an adjustable resistance. Such adjustable resistance can also serve for the exact adjustment of the igniter.

In all the exemplary embodiments of igniters hereinbefore described, in accordance with the invention, upon use, only the storage condensers a are charged from a source of current and supplied with the total energy necessary for the igniter. This, aside from the greater safety obtained for introducing the energy into the igniter, permits simplifying the igniter in an advantageous way and they also only have means (connecting terminals) for introducing electrical energy into their storage condensers.

It is possible, however, also to charge the ignition condenser initially with a certain voltage lying below the ignition voltage, and to provide it with the remaining energy necessary for producing an ignition with a definite delay from the storage condenser. This may be advantageous particularly in the case of time igniters, for example such as shown in Fig. 13, in order to make it possible to include all occurring times of ignition with a smaller range of voltage than is possible by simple charging of the storage condenser. For this purpose the igniting condensers of the igniters may also be provided with externally located connection terminals, as carried out, for example, in the igniter according to Fig. 13, the charging contact e_1 shown in dotted lines. In order to obtain various times of ignition, now the igniting condenser b and its storage condenser a are charged simultaneously, however, with mutually different voltages. Various conditions thereby becoming possible are illustrated by means of the diagram of Fig. 13a. Let it be assumed that the storage condenser a is given the initial voltage $+E_a$. Then the igniting condenser b may either be given a charge of the same kind, say $+E_b$.

In this case only a small amount of electricity need be introduced thereto from the condenser a , so that a rise in voltage according to the dotted curve S_{b2} will produce the ignition even after only a very short time t_3 .

It is, however, also possible to give the igniting condenser *b* a charge — E_{b1} , which has a polarity opposite to that of the storage condenser *a*. In combination with the initial voltage E_a of the storage condenser *a*, then a rise of voltage will occur in the ignition condenser *b* in accordance with the curve S_{b4} , and the ignition voltage E_z , and thereby an ignition, will be attained only at the materially later instant of time t_4 .

I claim as my invention:—

1. An electrical igniter wherein electrical capacity is used as storage means for the igniting current, comprising an ignition condenser which yields its energy in the form of ignition current, connected to a storage condenser which is chargeable from a source of current, from which said ignition condenser receives its entire energy or the partial amount still lacking for producing an ignition, and suitable means whereby said energy is supplied to the ignition condenser only after a certain delay after the completion of the charging of the storage condenser.

2. An igniter as in claim 1, wherein the ignition condenser is connected to the storage condenser through a high ohmic resistance.

3. An igniter as in claim 1, having also an igniting agent, and electrical leads between the said agent and the ignition condenser, one side of the storage condenser and one side of the ignition condenser being grounded to the body of the igniter, whereby one of the leads of the igniting agent is also brought to the potential of said body.

4. An igniter as in claim 1, having also an electrical ignition agent, and electrical leads between the said agent and the ignition condenser, one side of the storage condenser and one side of the ignition condenser being grounded to the body of the igniter, whereby one of the leads of the igniting agent is also brought to the potential of said body, and a percussion-closing contact in the discharge circuit of the ignition condenser, wherein the said percussion-closing contact is inserted between the igniting agent and that pole of the ignition condenser which is grounded to the body of the igniter.

5. Igniter in accordance with claim 1, having also means which are actuated upon and by the connection of a source of current to the storage condenser and which during the duration of said connection will prevent the flow of energy from the latter into the ignition condenser.

6. Igniter in accordance with claim 1, having also means which are actuated upon and by the connection of a source of current to the storage condenser and which during the duration of said connection will prevent the flow of energy from the latter into the ignition condenser, and having also a switch in the circuit connecting the storage condenser to the ignition condenser.

7. Igniter in accordance with claim 1, having also means which are actuated upon and by the connection of a source of current to the storage condenser and which during the duration of said connection will prevent the flow of energy from the latter into the ignition condenser, and having also a switch in the circuit connecting the storage condenser to the ignition condenser, the switch being connected in the circuit between the two condensers in positive connection with a movable contact element connected to or connectable to the storage condenser, so that upon contact of live parts with the storage condenser and during the charging of the latter which results, it automatically maintains the circuit opened between the two condensers.

8. Igniter in accordance with claim 1, having means which are actuated upon and by the connection of a source of current to the storage condenser and which during the duration of said connection will prevent the flow of energy from the latter into the ignition condenser, and a switch which positively short-circuits the ignition condenser and thereby the igniting agent connected thereto, and actuated upon and by the contact of live parts with the storage condenser.

9. Igniter in accordance with claim 1, having also means which are actuated upon and by the connection of a source of current to the storage condenser and which during the duration of said connection will prevent the flow of energy from the latter into the ignition condenser, a switch which when in charging position short-circuits the ignition condenser and at the same time disconnects it from the storage condenser and furthermore connects the latter with charging contact members which are connectable to a source of current, and in a second, normal position, disconnects the charging contact elements from the storage condenser, connects the latter to the igniting condenser and removes the short-circuit from the latter.

10. An electrical igniter wherein electrical capacity is used as storage means for the igniting current, including two independent electrical systems each comprising an ignition condenser which yields its energy in the form of ignition current, connected to a storage condenser which is chargeable from a source of current, from which said ignition condenser receives its entire energy or the partial amount still lacking for producing an ignition, and suitable means whereby said energy is supplied to the ignition condenser only after a certain delay after the completion of the charging of the storage condenser.

11. Igniter in accordance with claim 10 which has two condenser arrangements provided with percussion-closing contacts in the ignition circuits of their ignition condensers, one of which is provided with means for attaining a percussion ignition "with delay"

and the second of which is provided with such for obtaining an ignition "without delay".

12. Igniter in accordance with claim 10, 5 wherein, in the charging lead of the storage condenser of the condenser arrangement with a percussion ignition operating "without delay", there is connected a relay, which makes the storage condenser chargeable only by 10 means of a charging voltage of definite magnitude.

13. Igniter in accordance with claim 10 for operation above and below water, characterized by the fact that it is provided with two 15 condenser arrangements each having a storage condenser and an ignition condenser operating upon an igniting agent through a switch, wherein the condenser arrangement operating for above-water targets is dischargeable when the igniter strikes water by 20 means of water contacts short-circuiting its condensers, before the production of an ignition, whereas the igniting condenser of the second condenser arrangement which operates upon under-water targets, is connected to 25 its storage condenser only upon the igniter striking water, by means of a water contact, in order to take up energy from said storage condenser, whose reverse discharge through 30 its charging connections is completely or partly prevented, by means of discharge tubes or similar means.

14. Igniter in accordance with claim 1, which contains a plurality of igniting condensers which deliver their energy as igniting currents through electrical igniting agents, which are fed by a common storage condenser which is chargeable from a source of current.

40 15. Igniter in accordance with claim 1, which contains a plurality of igniting condensers which deliver their energy as igniting currents through electrical igniting agents, which are fed by a common storage 45 condenser which is chargeable from a source of current, and wherein an igniting condenser is disconnected through a percussion-closing contact and an igniting agent operating "with delay" through a high ohmic resistance, and a 50 second igniting condenser operating "without delay" through a percussion-closing contact and an igniting agent is connected through a high ohmic resistance and a discharge tube connected in series therewith to 55 a common storage condenser.

16. Igniter in accordance with claim 1, for operation over or under water, and having two igniting condensers which are feedable from a common storage condenser through 60 high ohmic resistances each operating through a percussion-closing contact and an igniting agent, one of which igniting condensers, operating upon targets above water, upon striking of the igniter against water, is 65 dischargeable by means of a short-circuit-

ing water contact before producing an ignition, whereas the second igniting condenser, which becomes active upon under-water targets, is connected to the storage condenser for receiving energy only when the igniter strikes water, by means of a water contact.

70 17. Igniter in accordance with claim 1, wherein a percussion-closing contact and simultaneously a discharge tube are provided in the discharging circuit of an ignition condenser, whereby the energy of the same serves for producing a percussion ignition as well as a time ignition.

75 18. Igniter in accordance with claim 1, wherein a percussion-closing contact and simultaneously a discharge tube are provided in the discharging circuit of an ignition condenser, whereby the energy of the same serves for producing a percussion ignition as well as a time ignition, and wherein the percussion-closing contact and the discharge tube are connected in parallel to one another in a manner known per se, and in series with a single igniting agent.

80 19. Process for providing energy to and timing electric igniters in accordance with claim 1, wherein in order to produce a time ignition a break-down discharge gap is introduced into the discharge circuit of an ignition condenser wherein the charging voltage of the storage condenser is varied for 85 attaining various times of ignition.

90 20. Process for providing energy and timing electrical igniters in accordance with claim 1, wherein in order to produce a time ignition a discharge gap is inserted into the discharge circuit of an ignition condenser and the ignition condenser and its storage condenser are charged simultaneously but 95 with mutually different voltages, in order to vary the nature of the ignition.

100 21. Process for providing energy to electrical igniters in accordance with claim 1, consisting in charging from a source of current only the storage condenser of the igniter, with the entire amount of energy required in the igniter.

110 22. An electrical igniter in accordance with claim 1, which contains only one means for introducing electrical energy into its storage condenser.

In testimony whereof I affix my signature.

HERBERT RÜHLEMANN.
